FIG. 5.

UNITED STATES PATENT OFFICE

2,225,461

ELECTRIC LIGHT SOCKET

Robert L. Reynolds, Los Angeles, Calif.

Application November 22, 1938, Serial No. 241,778

5 Claims. (Cl. 173—332)

This invention relates to and has for an object the provision of a novel construction and arrangement of companion male and female units of electrical connectors, such as a socket and a lamp, a socket and a plug, a fuse block and a fuse, or any two related and detachable devices for establishing an electrical connection, wherein such construction and arrangement renders both units shock-proof and makes possible a quick and easy coupling and uncoupling of said units without the use of screw threaded parts, bayonet joints or other coupling means requiring rotation of either unit.

Another object of this invention is to provide a connector such as described wherein the contact members of the companion units are in the form of tubes of circular cross section arranged to be telescopically engaged and frictionally maintained in proper contact with one another without necessitating the turning of one unit relative to the other to bring the contacts into a predetermined position other than axial alignment before "plugging" one in the other.

A further object is to provide a connection wherein the tubular contact members may be effectively secured in place without screws or the like and will provide a strong and rugged construction with the contact members of the line connected unit, such as a socket, countersunk in the body of insulation material whereby to prevent short circuiting, shocks and distortion or other damage to contact members themselves.

With the foregoing objects in view, together with such other objects and advantages as may subsequently appear, the invention is carried into effect as illustrated by way of example in the accompanying drawing, in which:

Fig. 1 represents a side elevation of socket and lamp constructed in accordance with this invention and as when coupled;

Fig. 2 represents an enlarged fragmentary vertical section taken on the plane of line 2—2 of Fig. 1;

Fig. 3 represents a sectional view taken on line 3—3 of Fig. 2;

Fig. 4 represents a sectional view taken on line 4—4 of Fig. 2;

Fig. 5 represents a sectional view taken on line 5—5 of Fig. 2;

Fig. 6 is a fragmentary perspective view of the base of the lamp constructed in accordance with this invention;

Fig. 7 is a perspective view of inner or center contact member of the socket;

Fig. 8 is a sectional view of a fuse embodying the construction of this invention;

Fig. 9 is a sectional view of a fuse block on socket embodying the construction of this invention.

As shown in the accompanying drawing, the invention hereof whether embodied in a socket and lamp as shown in Figs. 1 to 7 inclusive or in a fuse unit as shown in Figs. 8 and 9, or in any other electrical connector, generally includes related and detachable connector units A and B having tubular and concentric contact members A¹ and A² and B¹ and B² arranged to be telescopically engaged by merely plugging one unit in the other after bringing the contact members into position of axial alignment. Such units are frictionally held in contacting relation and it is seen that they may be quickly and easily connected without the use of screw threaded, bayonet or other rotative joints, and that it is only necessary to bring the contact members into axial alignment in order to plug one unit in the other. In all cases, the line connected or "hot" unit has its contacts countersunk in an insulation body portion to prevent shocks, short circuiting and damage to the contacts themselves.

Referring more specifically to the socket and electric lamp units shown in Figs. 1 to 7 inclusive, it is seen that the socket includes the usual cylindrical two-part metal outer shell 1 which houses a body 2 of insulation material and a frictionally retained metal shell 3 having a slotted lower end forming a plurality of gripping tongues or jaws 4. The shell 3 is reduced between its ends to form an annular shoulder 5 for supporting the body 2 and the upper end of said inner shell is crimped over the upper end of the body 2 as at 6 after the body is inserted in place.

The tubular contact member A¹ is mounted in an annular recess 7 centrally of the body 2 and is provided with slots 8 defining a plurality of spring contact fingers 9 which are outwardly flared and terminate in inwardly spaced relation to the outer extremities of the recess 7 but in position to be contacted when the contact B¹ of the companion unit is inserted in said recess. Tongues 10 are provided on the inner end of the tubular contact A¹ and are inserted through openings 11 registering with the inner end of the recess 7, then bent to lie in recesses 12 at the upper ends of the openings 11 and cemented over as at 13, whereby to secure the contact A¹ to the body 2.

For the purpose of connecting the contact A¹

with a line conductor 14, a tubular binding post 15 is formed integral with the upper end of the contact A¹ and extended upwardly from the top of the body 2 through an opening 16 therein. To 5 avoid stripping the insulation from the conductor 14, the end of the conductor is inserted in the upper end of the post 15 and a contact staple 17 is inserted laterally through aligned holes 18 in said post, in such manner as to engage the wire 10 as shown in Fig. 2. This provides for an easily effected and quick detachable connection of the conductor and insures a proper electrical connection.

The outer contact member A² is mounted in 15 an annular recess 19 concentric with and similar to the annular recess 7 and is substantially identical with the contact A¹ except as to size, in that it is provided with contact fingers 9' and 10', and a tubular binding post 15' for the other 20 conductor 14'. The ends of the contact fingers 9' are spaced inwardly from the outer end of the recess 19 as are the fingers 9 in the recess 7; both side walls of each of the annular recesses 7 and 19 being part of the insulation body 2, 25 and terminating on a common plane in outward spaced relation to the tips of the contact fingers 9 and 9' so that bodies of insulation protrude outwardly from the interior and the exterior of the outer end portions of the contact fingers 9 30 and 9' of the contact members A¹ and A². This arrangement of the contact fingers 9 and 9' prevents shock and short circuits and protects the contacts from distortion and other damage.

The lamp includes the usual bulb 20 and 35 filament conductors 21, the bulb being cemented in a metal base 22. The upper part of the base 22 forms the annular or tubular contact member B² which is adapted to be received in the recess 19 and to be frictionally engaged with fingers 9' as shown in Fig. 2.

The inner contact member B¹ of the lamp is in 40 the form of a cup the bottom of which is interlocked with a disk 23 of insulation material set 45 interiorly of the contact B₂. The filament conductors are connected as at 24 and 24' respectively with the contacts B¹ and B². The outer end portion of the annular side wall of the contact B¹ is formed with an annular groove or indentation 25 whereby to frictionally and releasably interlock with the fingers 9 when the contact B¹ is thrust into the recess 7 so as to engage said fingers as shown in Fig. 2.

When the base of the lamp is inserted into the socket the tongues or jaws 4 will frictionally 55 retain the base in the socket, it being noted that a spacer sleeve 27 of compressible paper or the like is interposed between these jaws and the shell, whereby to accommodate a yielding movement of said jaws.

In Figs. 8 and 9, the connectors are in the 60 form of a fuse socket or block 28 and a fuse 29, which include the tubular contacts A¹ and A² and B¹ and B² of substantially the same construction and arrangement as the corresponding 65 contact members in the lamp socket and lamp shown in Fig. 2. The fuse block has annular concentric recesses 30 and 31 and the contacts A¹ and A² are fitted therein as are the contacts of the lamp socket. Tongues 32 formed integral 70 with the contacts A¹ and A² are extended laterally through openings 33 in the block and have binding posts 34 at their outer ends for connection with line conductors not shown. The contacts A¹ and A² are countersunk as are the 75 socket contacts and for the same purpose.

The fuse 29 consists of a body 35 of insulation material to which the concentric tubular contacts B¹ and B² are fixed so that they may be telescopically engaged with the block contacts A¹ and A². Certain terminals of the contacts 5 B¹ and B² extend into a covered recess 36 having a closure 37. A fuse element 38 mounted in said recess is connected across said terminals. This fuse unit is subject to being readily inserted and withdrawn and will be securely frictionally held in place. 10

I claim:

1. An electrical connector including a pair of 15 separable connecting devices, concentric tubular male contact members mounted in spaced relation to one another on one of said devices, similarly spaced concentric tubular female contact members carried by the other of said devices and adapted to be telescopically engaged with the contacts of the first named device, said second 20 named device having concentric annular recesses in which the tubular female contacts thereof are mounted so as to be engaged with first named contacts upon entrance of the latter into said recesses, and said female contacts having 25 their tips spaced inwardly from the plane of the margins of the walls of said recesses.

2. An electrical connector including a pair of 30 separable connecting devices, concentric tubular male contact members mounted in spaced relation to one another on one of said devices, similarly spaced concentric tubular female contact members carried by the other of said devices and adapted to be telescopically engaged with the contacts of the first named device, said second 35 named device having concentric annular recesses in which the tubular female contacts thereof are countersunk with their outer ends spaced inwardly from the plane of the margins of the inner and outer walls of said recesses so 40 as to be engaged with first named contacts only after entrance of the latter into said recesses.

3. An electrical connector including a pair of 45 separable connecting devices, concentric tubular male contact members mounted in spaced relation to one another on one of said devices, similarly spaced concentric tubular female contact members carried by the other of said devices and adapted to be telescopically engaged with the contacts of the first named device, said second 50 named device having concentric annular recesses in which the tubular female contacts thereof are mounted with their outer ends recessed 55 relative to the plane of the margins of said recesses so as to be engaged with first named contacts upon entrance of the latter into said recesses, certain of the companion contacts having cooperating convex and concave portions adapted to releasably and frictionally interlock. 60

4. An electrical connector including a pair of 65 separable connecting devices, concentric tubular male contact members mounted in spaced relation to one another on one of said devices, similarly spaced concentric tubular female contact members carried by the other of said devices and adapted to be telescopically engaged with the contacts of the first named device, said second 70 named device having concentric annular recesses in which the tubular female contacts thereof are countersunk with their outer ends spaced inwardly from the plane of the margins of the inner and outer walls of said recesses so 75 as to be engaged with first named contacts only after entrance of the latter into said recesses. 75

said female contacts being slotted to define a plurality of resilient contact jaws.

5. An electrical connector including a pair of separable connecting devices one of which constitutes a socket member having a body of insulation material formed with a pair of concentric annular recesses, a tubular female contact member arranged in each of said recesses having its outer end spaced inwardly relative to the plane 10 of the margins of the side walls of its recess whereby said contact members are housed com-

pletely within said body of insulation material with the outer ends of said contact members counter-sunk therein, and the other of which connecting devices embodies an end disc of insulation material and a pair of spaced concentric tubular contacts protruding from said disc adapted to be inserted in the annular recesses of the body of the other connecting device into electrical connection with the tubular contacts therein.
